Primary Examiner — Holly Baynham

(**) Term: **14 Years**

(57) **CLAIM**

(21) Appl. No.: **29/457,736**

The ornamental design for an electromagnetic shield for a wallet, as shown and described.

(22) Filed: **Jun. 12, 2013**

DESCRIPTION

(51) **LOC (10) Cl.** **03-01**

FIG. 1 is a front elevation view of an electromagnetic shield for a wallet showing my new design, the opposite side being a mirror image of the shown;

(52) **U.S. Cl.**
USPC **D3/318**

FIG. 2 is a right side elevation view thereof, the opposite side being a mirror image of the shown;

(58) **Field of Classification Search**
USPC D3/318; 150/130, 132, 136–137, 147;
361/818

FIG. 3 is a top plan view thereof, the opposite side being a mirror image of the shown; and,

See application file for complete search history.

FIG. 4 is an isometric view thereof.

(56) **References Cited**

The dot-dashed broken lines representing a wallet are for the purposes of illustrating environment and form no part of the claimed design. The evenly spaced broken lines represent removable sections and are part of the claimed design.
